UNITED STATES PATENT OFFICE.

CARL STROHKORB, OF BERLIN, GERMANY.

CARRIAGE FOOT-BRAKE.

No. 892,769.

Specification of Letters Patent.

Patented July 7, 1908.

Application filed November 27, 1907. Serial No. 404,038.

To all whom it may concern:

Be it known that I, CARL STROHKORB, a subject of the German Emperor, and resident of 7 Neue Promenade, Berlin, Germany, have 5 invented certain new and useful Improvements in Carriage Foot-Brakes, of which the following is a specification.

My invention relates to carriage foot brakes and consists of an arrangement for 10 the application and release of carriage brakes in which, by depressing a foot-lever placed by the driver's seat, a tension link, which applies the brake, is wound onto a drum; by 15 depressing a second foot-lever the brake is released.

The essential feature of the invention is that the winding drum is placed on its shaft in such a manner that it can be moved, so that it can be brought into action or released 20 by means of two pawls, one of which is connected to the foot-lever which applies the brake, and is therefore the operating pawl.

As the application and release of the device is carried out by means of two foot-levers 25 placed one behind the other in the same vertical plane, it is possible to operate these levers immediately with one foot only.

In consequence of the method of supporting the pawls which operate the winding 30 drum, by means of a smooth disk of corresponding diameter, common to both, they do not rest directly on the ratchet wheel attached to the drum, and, therefore, allow the device to be easily applied or released without 35 shock or noise, by simply moving the drum.

In the accompanying drawing Figure 1 shows a general diagrammatic view of the device which is shown as a hub-brake. Fig. 40 2 is a side view of the brake gear, with the side wall removed. Fig. 3 is a front view, and Fig. 4 is a view from below, on a larger scale.

A spindle 2 is fixed to a frame or lattice 45 support 1 placed under a cover, in such a manner that it can rotate; a smooth circular disk 3 and two lever-arms 4, placed close to the same, are tightly keyed on to the spindle 2. At their outer projecting ends, these 50 arms 4 are connected to an operating or foot-lever 5 so that they can be moved. In order to insure that its movement is properly and forcedly guided, this lever 5 is connected to the frame 1 by means of a link 6. On the 55 spindle 2 a drum 7 is placed in such a manner that it can be moved but not rotated; it has

a ratchet wheel 8 rigidly attached to its side. On the opposite side of the drum 7 a roller 9 provided with a ring-nut is fixed, which engages with a lever 10 at its forked end. This 60 lever 10 is intended to move the drum 7 when required, and to release the ratchet-wheel 8 from the pawls 13 and 14. The lever 10 is fixed to a pivot 18 at a suitable place inside the frame, in such a way that it can be 65 turned. The width of the ring-nut of the roller 9 is so chosen that it permits the slight movement necessary for the lever 10 inside the nut, to take place freely (Fig. 3). At its other end the forked lever 10 is connected by 70 a link to a rod 11 which projects above the cover 1 and which is provided with a plate 19 at its upper end. On the free end of the spindle 2 a spiral spring 12 is placed, which bears against the drum 7 and serves the pur- 75 pose of keeping the latter in the position shown in Fig. 3. In this position, a pawl 13 fixed to the lever 4, and the pawl 14, fixed to the frame 1, are engaged with the ratchet-wheel 8. The spring 12 also serves the pur- 80 pose, after the depression of the lever 11, 10, and the subsequent release of the lever 11, to return the drum 7 to its original position, whereupon the released lever 11, 10, owing to the indirect action of this spring, is also 85 returned to its first position.

The pawls 13 and 14 are pressed onto the ratchet-wheel 8 by means of springs; apart from these, however, they rest on the disk 3, the diameter of which corresponds to that of 90 the ratchet-wheel less the length of the teeth. The object of this arrangement is to allow a quick, easy and noiseless operation of the drum 7 with regard to releasing it or engaging it with the pawls. The depressed foot-lever 95 4, 5 will always be returned to its first position by means of a spring 16. The tension link 20 (belt or similar arrangement), which is attached to the drum 7 and is wound onto the latter when the lever 4, 5 is depressed, 100 operates a band brake 21 (Fig. 1) to which it is attached, in the well known manner by a double lever, and applies the brake.

In order to release the brake, the foot lever 11 is depressed, as already mentioned, where- 105 upon the drum 7 disengages the pawls 13, 14 from the ratchet-wheel 8.

In order to prevent the brake, when in the applied position, from being accidentally or unintentionally released, a fixing device 17 110 is provided and is fixed to a spindle 22; it can be turned by means of a key 23 (Fig. 3)

so that it comes into contact with the ratchet-wheel 8, whereupon the drum 7 cannot be moved or disengaged from the pawls.

The operating and release levers 5 and 11 5 lie in the same vertical plane, as already mentioned so that the brake may be operated with one foot; it may, moreover, be operated instantaneously.

What I claim as my invention and desire to 10 secure by Letters Patent of the United States, is—

1. In a foot brake for carriages in combination with the actual brake means, a frame, a spindle turnably arranged in the latter, a 15 drum shiftably fixed on the said spindle, a tension link connected to the said drum and to the actual brake means, a foot lever for turning the said drum, a ratchet-wheel rigidly connected to the said drum, detent 20 means adapted to engage with the said ratchet wheel, and a second foot lever for shifting the said drum together with the said ratchet wheel, to disengage the latter from the said detent means, substantially as and 25 for the purpose set forth.

2. In a foot brake for carriages in combination with the actual brake means, a frame, a spindle turnably arranged in the said frame, a drum shiftably fixed on the said spindle, 30 a tension link connected to the said drum and to the actual brake means, an intermediate lever fastened to the said spindle, and a foot lever connected to the said intermediate lever, a ratchet wheel fastened to the 35 said drum, a pawl connected with the said intermediate lever and adapted to engage with the said ratchet wheel, a pawl fastened to the said frame and also adapted to engage with the said ratchet wheel, and a second 40 foot lever for shifting the said drum together with the said ratchet wheel, to disengage the latter from the said two pawls, substantially as and for the purpose set forth.

3. In a foot brake for carriages, in combination with the actual brake means, a frame, 45 a spindle turnably arranged in the said frame, a drum shiftably fixed on the said spindle, a tension link connected to the said drum and to the actual brake means, an intermediate lever rigidly connected to the 50 said spindle, and a foot lever connected to the said intermediate lever, a ratchet wheel fastened to the said drum, a pawl connected with the said intermediate lever and adapted 55 to engage with the said ratchet wheel, a pawl fastened to the said frame and also adapted to engage with the said ratchet wheel, a grooved roller rigidly connected to the said drum, a double-armed lever turn- 60 ably arranged in the said frame and having its one forked end in engagement with the said grooved roller, a second foot lever connected to the other end of the said double- 65 armed lever, and a spring on the said spindle for holding the said drum in its normal posi-

tion, substantially as and for the purpose set forth.

4. In a foot brake for carriages, in combination with the actual brake means, a frame, a spindle turnably arranged in the said frame, a drum shiftably fixed on the said spindle, a tension link connected to the said drum and to the actual brake means, an intermediate lever rigidly connected to the said spindle, a foot lever connected to the said intermediate lever and a spring for holding the said intermediate lever and the said foot lever in the normal position, a ratchet-wheel fastened to the said drum, a disk with a smooth circumference fastened to the said spindle and having a diameter which corresponds to that of the said ratchet wheel, less the length of the teeth, a pawl connected with the said intermediate lever and adapted to engage with the said ratchet wheel, a pawl fastened to the said frame and also adapted to engage with the said ratchet wheel, the two said pawls resting on the circumference of the said disk, a grooved roller rigidly connected to the said drum, a double armed lever turnably arranged in the said frame and having its one forked end in engagement with the said grooved roller, a second foot lever connected to the other end of the said double-armed lever, a spring on the said spindle for holding the said drum in its normal position of the latter, substantially as and for the purpose set forth.

5. In a foot brake for carriages, in combination with the actual brake means, a frame, a spindle turnably arranged in the said frame, a drum shiftably fixed on the said spindle, a tension link connected to the said spindle and to the actual brake means, an intermediate lever rigidly connected to the said spindle, a foot lever connected to the said intermediate lever, and a spring for holding the said intermediate lever and the said foot lever in the normal position, a ratchet wheel fastened to the said drum, a disk with a smooth circumference fastened to the said spindle and having a diameter which corresponds to that of the said ratchet wheel, less the length of the teeth, a pawl connected with the said intermediate lever and adapted to engage with the said ratchet wheel, a pawl fastened to the said frame and also adapted to engage with the 100 said ratchet wheel, the two said pawls resting on the circumference of the said disk, a grooved roller rigidly connected to the said drum, a double armed lever turnably arranged in the said frame and having its one 105 forked end in engagement with the said grooved roller, a second foot lever connected to the other end of the said double-armed lever, a spring on the said spindle for holding the said drum in its normal position, an axle 110

turnably arranged in the said frame, a locking piece fixed on the said axle and adapted to secure the said drum and ratchet wheel in the engaging position of the latter, and 5 means to turn the said axle and locking piece, substantially as and for the purpose set forth.

In testimony whereof I have hereunto

signed my name this 14th day of November 1907, in the presence of two subscribing witnesses.
